DESIGN FOR AN INSULATING SUPPORT FOR AN ELECTRICAL HEATING ELEMENT

Ralph Carifi, Newark, N. J.

Application December 8, 1945, Serial No. 124,521

Term of patent 3½ years

(Cl. D26—10)

To all whom it may concern:

Be it known that I, Ralph Carifi, a citizen of the United States, residing at Newark, in the county of Essex and State of New Jersey, have invented a new, original, and ornamental Design for an Insulating Support for an Electrical Heating Element, of which the following is a specification, reference being had to the accompanying drawing, forming part thereof.

Fig. 1 is a perspective view of an insulating support for an electrical heating element, embodying my invention.

Fig. 2 is another perspective view of the insulating support shown in Fig. 1.

Fig. 3 is an end view of the insulating support shown in Fig. 1.

Fig. 4 is a top plan view of the insulating support shown in Fig. 1.

Fig. 5 is a cross sectional view taken on line 5—5 of Fig. 4 in the direction of the arrows.

I claim:

The ornamental design for an insulating support for an electrical heating element, as shown.

RALPH CARIFI.
